WINDROWER

Paul R. Schroepel, Rockford, Ill., assignor to J. I.
Case Company, Racine, Wis., a corporation

Application July 24, 1942, Serial No. 452,181

2 Claims. (Cl. 56—23)

1

The present invention relates to harvesting machinery and more particularly to windrowers, and an object of the invention is to generally improve the construction and operation of machines of this class. More specifically, an object of the invention is to improve the frame-work and general construction of such machines. A further object is to provide a novel drive for the reel and incidentally, to provide for actuating the conveyor which is located across the discharge opening from the other parts of the machinery.

Further objects and advantages will become apparent from the following specification and accompanying drawings in which a satisfactory embodiment of the invention is shown. However, it is to be understood that the invention is not limited to the details disclosed but includes all such variations and modifications as fall within the spirit of the invention as herein expressed.

Figure 1 of the drawings is a rear elevation of a windrower or windrow harvester embodying the invention.

Fig. 2 is a perspective view of a portion of the same taken from in front and to the left with parts removed and others broken away.

Fig. 3 is a detail of certain mechanism indicated in Fig. 1.

Fig. 4 is a plan view with parts broken away of certain mechanism indicated in Fig. 2, and

Fig. 5 is an enlarged plan view, diagrammatic in character of certain mechanism indicated in Fig. 1.

As seen in Fig. 1, the machine comprises a frame generally designated as F carried by ground wheels W¹ and W², frame F carrying a cutter bar generally designated as C and a platform generally designated as P. Platform P is spaced from wheel W¹ to provide a delivery opening D. Frame F also carries a reel R and in fact substantially all of the various parts commonly associated with a machine of this character.

In the present instance, wheel W¹ is journaled on an axle 10, Fig. 2, carried in a frame portion generally designated as 11 and comprising longitudinal members 12 and 13 and front and rear cross members 14 and 15, Fig. 1, members 13 and 14 being united by a portion 16, Fig. 2. The various portions form a roughly rectangular frame surrounding and enclosing wheel W¹ and generally disposed in a horizontal plane. Cutter bar C originates at frame portion 11 and extends laterally of the machine at the lower front portion thereof. Between wheel W¹ and platform P is an upstanding wall 17 connected with member 13 and serving as a part of the structure and

also to shield wheel W¹ from material being deposited through opening D. A tubular element 18 (see also Fig. 1) is connected with member 15 of frame portion 11 preferably by a clip-like element 19 and extends inwardly and upwardly to a point of connection 20 with above mentioned wall 17. Member 18 then extends across the machine substantially parallel to cutter bar C and unites with end structure 21 carried in any suitable or well-known manner on wheel W². Platform P is carried on structure 21, by cutter bar C, and also by a strut 22 depending from tubular element 18. Platform P is spaced appreciably from wall 17 so as to leave above mentioned opening D for the deposit of the harvested material in the form of a windrow as the machine moves along.

With the structure thus far described, it will be seen that tubular member 18 forms the major structural unit in the machine and carries the major downward loads resulting from the weight of the machine and the crop being cut. It is also very strong in torsion and resists warping or twisting of platform P due to the backward reaction of the cutter bar which is unavoidably applied to frame portion 11 and end structure 21 at a point spaced below member 18, thus resulting in a twisting force in member 18. A draw bar 23 is pivoted at 24 and 25 to the forward part 30 of frame portion 11 and is adjustable in its angular relation therewith by a lever 26 pivoted at 27 to drawbar 23 and cooperating with a quadrant member 28 fixed with draw bar 23. A link 29 pivoted to lever 26 at 30 extends back to 35 a pivotal connection 31 with a portion of upstanding wall 17. A detent member 32 on lever 26 maintains lever 26 in adjusted relation with quadrant 28 in well-known manner and accordingly maintains the adjustment of draw bar 23, or rather frame portion 11 relatively to draw bar 23.

The several parts of the machine are actuated from wheel W¹. In the present instance a sprocket 33 fixed with the wheel drives, through 45 a chain 34, a sprocket 35 Fig. 5 on a shaft 36. Shaft 36 drives a bevel gear 37 which drives a bevel gear 38 on a shaft 39, the several shafts and gears being carried in a casing 40. Shaft 39 as more particularly seen in Fig. 2, carries a crank 41 engaged by a pitman 42 connected to a sickle 43 which is reciprocated in the usual manner by rotation of shaft 39.

Platform P has an apron or draper 44, Fig. 1, traveling about rollers 45 and 46 for feeding the 55 cut crop toward delivery opening D. Roller 45

is fixed with a shaft 47 on which is mounted, in the present instance, a pulley 48. On above mentioned shaft 39 is a pulley 49 from which motion is transmitted from shaft 39 to shaft 47 as will appear.

Upstanding wall 17 carries a standard 50 which extends upwardly and to the right as seen in Fig. 1, to a point partially over above mentioned opening D. At this point a fitting 51 provides a bearing 52 for shaft 53 on which is fixed a pulley 54. Fitting 51 also provides a fulcrum 55 Fig. 3, for a lever 56 with which is fixed a stud or journal 57. A sheave or idle pulley 58 is rotatably carried on journal 57 and a tension member 59 adjustably connects lever 56 with standard 50. Adjustment of member 59 will accordingly raise or lower pulley 58.

A belt 60 extends about above mentioned pulley 49, upwardly and over pulley 54, downwardly and about pulley 48, upwardly and over pulley 58, and again downwardly to above mentioned pulley 49. In this manner belt 60 is carried across opening D and will not interfere with the depositing of material behind the machine. Rotation of shaft 39, however, will drive shaft 47 and also pulleys 54 and 58 by virtue of movement of belt 60 caused by rotation of pulley 49.

As seen more particularly in Fig. 2, reel R is built about a shaft 61 carried in a bearing 62 supported on a standard 63 carried in any suitable or well-known manner in the present instance from wall 17. Standard 63 is slidable on a staff 63^a supported from wall 17 by a bolt or the like 63^b and is welded or otherwise suitably secured to bearing 62 in well-known manner, a pin 63^c engaging one or another of holes 63^d in staff 63^a for determining the height of bearing 62. Shaft 61 has a bevel gear 64 meshing with a bevel gear 65 carried in a bearing portion 66 supported from bearing 62. Bevel gear 65 is connected by a tumbler shaft of well-known construction generally designated as 67 with above mentioned shaft 53, Fig. 1. Accordingly motion of belt 60 in rotating pulley 54 will cause rotation of reel R.

Reel shaft 61 is supported at its other end by a bearing 68 on an arm 69 fulcrumed at 70 to a curved arm or standard 71 extending upwardly and forwardly from above mentioned structure 21. A tension member 72 also connected with standard 71 is adjustable in length in well-known manner for changing the position of arm 69. Above mentioned bearing 62 is also adjustable in position in well-known manner forming no part of the present invention.

A windshield 73 is arranged behind platform P and attached to structure 21 and strut 22 to prevent blowing of material on conveyor 44, and extending substantially to the left extremity of conveyor 44 as shown in Fig. 1. A roller 74, in the present instance of angular cross section, is supported substantially parallel to roller 45 and has a shaft 75 carrying a pulley 76. Pulley 76 is driven by a short belt 77 from a pulley 78, in the present instance immediately behind above mentioned pulley 48 on shaft 47. Roller 74 catches material being discharged from conveyor 44 and assists in guiding it into opening D. In this manner any tendency for material to follow around beneath conveyor 44 is substantially eliminated. Roller 74, as clearly shown in Fig. 1,

projects somewhat beyond the end of windshield 73 into opening D.

In operation the machine is drawn by a tractor or other means attached to draw bar 23, the rotation of wheel W¹ actuating the several machine units as described, whereupon material is cut by cutter bar C, laid on conveyor 44 by reel R and conveyed by conveyor 44 into opening D, thus forming a continuous windrow behind the machine. The problem of conveying motion to conveyor 44 without encroaching upon opening D is solved by carrying belt 60 completely clear of opening D, frame 18 and windshield 73, on standard 50, the motion of belt 60 also serving to drive reel R.

The above being a complete description of an illustrative embodiment of the invention, what is claimed as new and desired to be secured by Letters Patent of the United States is:

1. A windrower having a frame generally transverse to the direction of movement thereof, a drive wheel at one end of the frame, a platform supported from the frame and spaced from the drive wheel to provide an opening for depositing a windrow, a conveyor on the platform for feeding cut crop to the opening, said frame including a portion extending about the drive wheel in a substantially horizontal plane, a sickle extending from said portion across the machine at the front thereof, said frame comprising a tubular member extending across the machine at a level above said sickle, an upstanding wall between said wheel and said opening, and said tubular member being united with said wall and bending down behind said wheel and being united with said aforementioned portion, a draw bar pivoted to said aforementioned portion and means for adjusting the angular relation between said frame portion and said draw bar.

2. A windrower having a frame generally transverse to the direction of movement thereof, a drive wheel at one end of the frame, a platform supported from the frame and spaced from the drive wheel to provide an opening for depositing a windrow, a conveyor on the platform for feeding cut crop to the opening, a shaft on the frame adjacent to the drive wheel and driven thereby, said frame including a portion extending about the drive wheel in a substantially horizontal plane, a standard on said portion extending upwardly therefrom to a point substantially over said opening, a driven shaft associated with said conveyor and on the opposite side of said opening from said drive wheel, a pulley on the first mentioned shaft, a pulley on said driven shaft, a plurality of pulleys on said standard, a belt extending from the first mentioned to the second mentioned pulley and supported above said opening on said pulleys on said standard, a sickle extending from said portion across the machine at the front thereof, said frame comprising a tubular member extending across the machine at a level above said sickle, an upstanding wall between said wheel and said opening, and said tubular member being united with said wall and bending down behind said wheel and being united with said aforementioned portion, a draw bar pivoted to said aforementioned portion and means for adjusting the angular relation between said frame portion and said draw bar.

3. A windrower having a frame generally transverse to the direction of movement thereof, a drive wheel at one end of the frame, a platform supported from the frame and spaced from the drive wheel to provide an opening for depositing a windrow, a conveyor on the platform for feeding cut crop to the opening, a shaft on the frame adjacent to the drive wheel and driven thereby, said frame including a portion extending about the drive wheel in a substantially horizontal plane, a standard on said portion extending upwardly therefrom to a point substantially over said opening, a driven shaft associated with said conveyor and on the opposite side of said opening from said drive wheel, a pulley on the first mentioned shaft, a pulley on said driven shaft, a plurality of pulleys on said standard, a belt extending from the first mentioned to the second mentioned pulley and supported above said opening on said pulleys on said standard, a sickle extending from said portion across the machine at the front thereof, said frame comprising a tubular member extending across the machine at a level above said sickle, an upstanding wall between said wheel and said opening, and said tubular member being united with said wall and bending down behind said wheel and being united with said aforementioned portion, a draw bar pivoted to said aforementioned portion and means for adjusting the angular relation between said frame portion and said draw bar.

4. A windrower having a frame generally transverse to the direction of movement thereof, a drive wheel at one end of the frame, a platform supported from the frame and spaced from the drive wheel to provide an opening for depositing a windrow, a conveyor on the platform for feeding cut crop to the opening, a shaft on the frame adjacent to the drive wheel and driven thereby, said frame including a portion extending about the drive wheel in a substantially horizontal plane, a standard on said portion extending upwardly therefrom to a point substantially over said opening, a driven shaft associated with said conveyor and on the opposite side of said opening from said drive wheel, a pulley on the first mentioned shaft, a pulley on said driven shaft, a plurality of pulleys on said standard, a belt extending from the first mentioned to the second mentioned pulley and supported above said opening on said pulleys on said standard, a sickle extending from said portion across the machine at the front thereof, said frame comprising a tubular member extending across the machine at a level above said sickle, an upstanding wall between said wheel and said opening, and said tubular member being united with said wall and bending down behind said wheel and being united with said aforementioned portion, a draw bar pivoted to said aforementioned portion and means for adjusting the angular relation between said frame portion and said draw bar.
